UNITED STATES PATENT OFFICE.

STANLEY W. NICHOLSON, OF TOLEDO, OHIO, ASSIGNOR TO THE DURA COMPANY, OF TOLEDO, OHIO, A CORPORATION OF DELAWARE.

WINDOW-CONTROLLING DEVICE.

Application filed December 6, 1920, Serial No. 428,642. Renewed November 25, 1921. Serial No. 517,500.

To all whom it may concern:

Be it known that I, STANLEY W. NICHOLSON, a citizen of the United States of America, residing at Toledo, in the county of Lucas and State of Ohio, have invented certain new and useful Improvements in Window-Controlling Devices, of which the following is a specification, reference being had therein to the accompanying drawings.

10 This invention relates to window controlling devices and more particularly to devices for controlling the raising, lowering and locking of sliding windows in motor vehicles.

15 The invention consists in the structural features and arrangement of parts herein-after fully set forth.

In the drawings:—

Figure 1 is an interior view of a motor vehicle door provided with a window equipped with a controlling device in accordance with the invention;

Figure 2 is a fragmentary perspective view of the controlling means;

25 Figure 3 is a cross section view of said means, the section being taken on line 3—3 of Figure 1.

In these views the reference character A designates a motor vehicle door having in 30 its upper portion a window opening, B, and having its lower portion chambered as indicated at B'. The closure for the opening B is formed by a vertical slideable plate of glass C which in lowered position is adapted 35 to enter the chamber B'. As is customary, there is provided suitable means for counterbalancing the weight of the glass plate C, this means consisting preferably of the pivotal arm D bearing upwardly at its free 40 end upon the lower edge of said plate and urged upwardly by a coiled spring E tensioned to exert the proper counterbalancing effort.

The bottom edge of the plate C is permanently engaged by a channel shaped strip from one end of which there is projected a tongue G to which is secured the lower extremity of a vertical actuating stem H. Said stem extends freely upwardly within a 50 tubular member I preferably formed of sheet metal and longitudinally slotted as indicated at I', said member is secured to the door A at one side of the window opening by screws I², and a series of notches J are 55 formed at regular space intervals in one

margin of said slot. Said stem is formed of a bar of spring steel herein shown square in cross section and adapted to function as a torsion spring, capable of withstanding twisting through a limited angle. The upper extremity of the stem is bent at a right angle as indicated at K, said bent end portion having a handle member L rigidly connected thereto, said handle being, in the structure shown, cast upon said bent extremity. The stem is so stressed as to urge said handle member against the notched margin of the slot to effect its latch engagement with any of the notches J with which said handle may be registered. Thus said handle and stem end provide a means for lifting or lowering the window, further constituting a latch means in conjunction with the tubular member I for holding the plate C in any desired position of adjustment. 75 A loop M may be provided in the stem H just above the point of attachment of said stem to the tongue G to increase the flexibility of said stem under torsional stress.

What I claim as my invention is: 80

1. In a window controlling device, the combination with a vertically adjustable window member, of a control stem having the nature of a torsion spring secured at its lower end to the lower portion of the window member, a combined handle and latch member, carried by the upper portion of said stem and a fixed latch element formed with a series of notches for engagement by said handle member in various positions of the window member. 85

2. In a window controlling device, the combination with a vertically adjustable window member and the frame thereof, of a control stem for said window member, having the nature of a torsion spring and secured at its lower end to the lower portion of the window member, a combined latch and handle member carried by the upper portion of said stem and a latch element 100 vertically extended upon the window frame engageable by said latch and handle member in various positions of the window member due to the normal torsion stress in the stem. 105

3. In a window controlling device, the combination with a vertically adjustable window member, of a control stem for said member having the nature of a torsion spring secured at its lower extremity to the 110

window member and having its upper end bent at a substantial right angle, a combined handle and latch member secured to said bent extremity and a tubular casing secured to the frame within which said stem is extended, said casing being vertically slotted and having a series of notches in the margin of said slot, said handle and latch member projecting outwardly through said slot and being urged against the notched margin of the slot by the normal stress of said stem whereby said handle member is adapted to engage in any of said notches with which it is registered to maintain the corresponding position of the window member.

4. In a window controlling device, the combination with a vertically adjustable window member and the frame thereof, of a notched latch member secured to said frame and a stem upwardly extending from the lower portion of said window member adjacent said latch member and having the nature of a torsion spring, said stem being looped to increase its flexibility, and a combined handle and latch member carried by the upper portion of said stem and urged by the torsional stress of the latter against said latch member and into engagement with any of said notches with which said handle and latch member may be registered.

5. In a window controlling device, the combination with a window frame and an adjustable window member, of a resilient control rod for said window member having one end operatively connected to the window member and complementary latch members upon said rod and frame respectively, the resiliency of the rod urging said latch members normally into engagement.

6. In a window control mechanism, a member having a window opening, a slidable closure for said opening, a chamber receiving said closure in open positions thereof, a rod mounted upon said closure controlling sliding thereof and rockable about its longitudinal axis to additionally control locking of said closure, said rod being accessible within said opening in all positions of said closure.

7. In a window control mechanism, a member having a window opening, a slidable closure for said opening, a chamber receiving said closure in the open positions thereof, a stationary locking member adjacent said opening elongated in the direction of travel of said closure, a rod carried by said closure substantially parallel with said locking member and extended upon the closure to permit access to said rod in all positions of the closure, said rod being rockable on its longitudinal axis, and a locking member fixed upon said rod normally engaging said

stationary locking member and releasable therefrom through rocking of said rod. 65

8. In a window control mechanism, a member having a window opening, a vertically slidable closure for said opening, a chamber below said opening receiving said closure in lowered positions thereof, a substantially vertical rod mounted at its lower extremity upon said closure and adapted to turn on its longitudinal axis, the upper end of said rod being free, a locking member fixed upon the upper end portion of said rod, and a coacting stationary locking member engageable in various positions of said closure by the first mentioned locking member through rocking of said rod. 70 75

9. In a window control mechanism, a member having a window opening, a slidable closure for said opening, a chamber receiving said closure in open positions thereof, a rockable rod carried by said closure and forming a control member therefor, a locking member fast upon said rod functioning also as a control handle for the rod, and a stationary locking member engageable by the first mentioned locking member through rocking of said rod, the latter being extended to locate said control handle in the window opening in all positions of said closure. 80 85 90

10. In a window control mechanism, a member having a window opening, a vertically slidable closure for said opening, a chamber below said opening receiving said closure in lowered positions thereof, a vertical tubular longitudinally slotted locking member adjacent said opening, a rod extending within said tubular member and mounted at its lower extremity upon said closure and adapted to turn on its longitudinal axis, and a locking member fixed upon the upper portion of said rod having a handle portion projecting through said slot normally engaged with the locking portion of said tubular member and disengageable therefrom by rocking of said rod, said handle being accessible within said window opening in all positions of said closure. 95 100 105 110

11. In a window control mechanism, a slidable window member, a frame within which said member slides, a stationary locking member upon said frame, a rod attached at one extremity to said slidable member and having adjacent its other end a locking portion rigid with said rod, said rod forming a control member for the window member and the locking element carried by said rod being engageable with and disengageable from the stationary locking member by a movement of the rod about its longitudinal axis. 115 120

In testimony whereof I affix my signature.

STANLEY W. NICHOLSON.
